(57) **CLAIM**

The ornamental design for a measurement and setback tool, as shown and described.

DESCRIPTION

FIG. 1 is a bottom, front, left side perspective view showing the design;

FIG. 2 is a bottom rear, right side perspective view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a top plan view thereof;

FIG. 8 is a bottom plan view thereof;

FIG. 9 is a bottom, front, right side perspective view in an alternate position; and,

FIG. 10 is a top, front, left side exploded perspective view. The broken line showing of a cord in FIGS. 1-6 and 8-10, is included for the purpose of illustrating unclaimed environment and forms no part of the claimed design. The remaining broken line portions in the figures are included for the purpose of illustrating portions of the measurement and setback tool and form no part of the claimed design.
